UNITED STATES PATENT OFFICE.

EMMA M. PALMER, OF COUNCIL BLUFFS, IOWA.

ABDOMINAL SUPPORTER.

1,150,300.

Specification of Letters Patent. Patented Aug. 17, 1915.

Application filed December 19, 1913. Serial No. 807,720.

To all whom it may concern:

Be it known that I, EMMA M. PALMER, a citizen of the United States, residing at Council Bluffs, in the county of Pottawattamie and State of Iowa, have invented certain new and useful Improvements in Abdominal Supporters, of which the following is a specification, reference being had to the accompanying drawings.

10 This invention relates to new and useful improvements in supporters and more particularly to an abdominal supporter and the primary object of the invention is to provide a device of this character which may be quickly and readily applied to use or removed and one which will be most effective in carrying out the purpose for which the same is designed.

20 A further object of the invention resides in providing a device of this character which is light of construction and so designed as to afford little or no inconvenience to the wearer.

25 Still another object of the invention resides in providing a device which is simple and durable in construction, inexpensive to manufacture and one which will be very efficient and useful in operation.

With these and other objects in view, the 30 invention consists in the novel features of construction, combination and arrangement of parts as will be hereinafter referred to and more particularly pointed out in the specification and claim.

35 In the accompanying drawings forming a part of this application, Figure 1 is a perspective view of a device constructed in accordance with my invention and in a position as worn on the body. Fig. 2 is a similar view showing the device in its outspread position prior to being applied to the body. Fig. 3 is a detail perspective view of the rear of the supporter with parts broken away. Fig. 4 is a detail perspective view of a portion of the shoulder supports of the device with parts in section. Fig. 5 is a sectional perspective view as seen on line 5—5, Fig. 1. Fig. 6 is a similar view as seen on line 6—6, Fig. 2. Fig. 7 is a similar view as seen on line 7—7, Fig. 2. Fig. 8 is a detail perspective view showing the ends of the upper section of the device brought together; and Fig. 9 is a detail perspective view of one end of the lower section of the supporter.

50 In describing my invention, I shall refer to the drawings in which similar reference

characters designate corresponding parts throughout the several views and in which 1 and 2 indicate, respectively, the upper and lower band sections which are secured together intermediate of their ends at a point indicated as 3 and at such point the device is braced by the back stays 4. The sections 1 and 2 which are formed of the usual or any preferred material used in the formation of devices of this character, are tapered so as to be increased in width toward their outer ends and said sections are provided, adjacent their free ends, with eyelets 5 with which may be engaged the laces 6 for securing the ends of said sections together about the body. The sections 1 and 2 are braced on each side of the rows of eyelets by means of the stays 7 and each section is provided adjacent one end thereof with a flap or tab 8 which is overlapped by the opposite end of the section when the ends of the sections are brought together, as clearly shown in Figs. 1 and 8 of the drawings. At predetermined points in the length of each of the sections 1 and 2 are provided the additional stays 9 which are secured in place in the usual or any preferred manner and the upper and lower edges of each of the sections are turned back and stitched, as shown at 10.

Secured to the outer face of the upper section 1, on opposite sides of the portion thereof indicated as 3, are the ends of a pair of shoulder straps 11 which are crossed and extend loosely through a keeper or the like 12. The opposite ends of said straps are adjustably secured, through the medium of buckles or the like 13 to the outer face of the section 1, adjacent the free ends thereof. Through the medium of these straps, the device is properly supported in position on the body and may be readily adjusted, as desired, in view of the buckle connections 13.

Engaged with the front and rear portions of the lower section 2, are the leg engaging 100 straps 14, said straps being adjustable by means of the buckle connections 15 arranged in their length. These straps are padded, as shown at 16, to prevent chafing and cutting of the skin and also aid in holding the support in proper position on the body of the wearer. Also secured to the lower section 2, adjacent the ends thereof, are the tabs or tongues 17, which depend therefrom and afford securing means for the adjustable 105 hose supporters 18.

Secured to the inner face of the upper

section 1, at points adjacent the ends thereof, are the hooks 19, and secured on the outer face of the lower section 2, adjacent the free ends thereof, are the eyes 20 and, 6 in applying this device to use, the hooks 19 are engaged with the eyes 20 to secure the upper and lower sections together. When so secured together, the upper section overlaps the lower section, said sections being 10 substantially dependent upon one another to serve as a unitary support for the abdomen of the wearer.

It will be noted that the upper band 1 is adapted for retaining the abdomen in its 15 normal position, while the lower band 2 is used for supporting the abdomen up and, at the same time retaining the same in, which taken in conjunction with the upper band 1, will absolutely support the abdomen 20 in its proper and normal position. It will be noted that by overlapping the sections at their meeting ends, it will form a continuous bearing surface against the front of the abdomen.

25 From the foregoing description of the construction of my improved abdominal supporter, the manner of applying the same to use will be readily understood and it will be seen that I have provided an improved 30 supporter which is simple and durable in construction, inexpensive to manufacture and one which will be very efficient and useful in operation.

35 While I have particularly described the elements best adapted to perform the functions set forth, it is obvious that various changes in form, proportion and in the

minor details of construction may be resorted to without departing from the spirit or sacrificing any of the principles of the 45 invention.

Having thus described this invention, what I claim is:—

An abdominal supporter comprising a body consisting of an upper and a lower 45 band-like section, said sections being adapted to overlap one another mid-way of their ends, a stay strap for permanently securing said sections in their overlapped positions, said upper and lower sections being provided with enlarged free ends, lacing means 50 engaged with and carried by said free ends to adjustably secure the same on the body of the wearer, the upper section being adapted to retain the abdomen in its normal 55 position and the lower section being adapted to support the abdomen and coact with the upper section for retaining the abdomen in its normal position, flaps secured to one of the free ends of the sections and adjacent 60 the lacing means, said upper and lower sections being spaced apart between the free ends and the mid-way portions thereof, shoulder straps, thigh straps consisting of 65 two portions connected to the lower section, and padding secured to the inner face of said thigh straps, as and for the purpose set forth.

In testimony whereof I hereunto affix my signature in the presence of two witnesses. 70

EMMA M. PALMER.
